COMBINED BOTTLE CLOSURE AND LIQUID DISPENSER

Le Roy P. Root, Brooklyn, N. Y., and Francis O'L. Killorin, Watertown, Conn., assignors to Scovill Manufacturing Company, Waterbury, Conn., a corporation of Connecticut

Application August 19, 1937, Serial No. 159,894

8 Claims. (Cl. 221—147)

Our invention relates to new and useful improvements in bottle closures and liquid dispensers, for dispensing liquids, preferably such liquids as have an undesirable odor, or injurious effect upon the person's hands or clothing handling the same, since it is very effective in the use of such liquids without spilling the same.

In practice this dispenser is normally applied to a container, such for instance as a bottle, 10 preferably one having a threaded circular neck portion to permit of the use of a threaded cap to insure an easy and secure attachment to the container.

An object of the invention is to so construct 15 the same as to form a shipping seal for the container to which it may be attached and thus require no auxiliary part for effecting a liquid tight seal.

A further and important object of the invention 20 is to provide a combined bottle closure and dispenser in a single unit which can conveniently be applied and removed from a container and which will be simple in construction, inexpensive to manufacture, convenient, durable and serv- 25 iceable.

More specific objects of the invention will become apparent from a consideration of the following description taken in conjunction with the drawing illustrating the construction and use of 30 the invention, and wherein:

Fig. 1 shows a perspective view of a bottle in an inverted position and provided with our improved dispenser which is shown supported and being operated as in the hand of an operator.

Fig. 2 shows a slightly enlarged vertical section of the dispenser shown in Fig. 1, applied to the neck of a bottle and in an upright position.

Fig. 3 shows an inverted plan view of the dispenser attached to a bottle.

Fig. 4 is a detached vertical cross section of the threaded attaching cap shown applied in Fig. 2 for retaining the compressible flexible diaphragm or top member in position.

Fig. 5 shows a similar vertical cross section 45 of the inner metal member of the dispenser, which includes a dropper, so-called.

Fig. 6 is a detached vertical cross section of the rubber diaphragm shown in Fig. 2, and

Fig. 7 shows a further vertical section of a 50 modified form of the dispenser.

The dispenser, as will be seen, is made up of comparatively few parts, two metallic members, a rubber diaphragm and a sealing washer. The same are constructed to be easily and effectively 55 assembled to form a single operative unit which

can readily be attached and detached from the neck of the container as in the dispensing of liquid. The operation of this dispensing is obviously governed entirely by the amount of pressure exerted on the rubber diaphragm after the 5 dispenser has been detached from the container. In fact, it may be used either in the form of a dropper, or dispenser of liquids in larger quantities. The use of the dispenser is not necessarily confined to medical solutions and disinfectants, but is equally well adaptable for perfumes, toilet water, etc.

A distinguishing feature of our present dispenser is that the container to which the dispenser is applied requires, for the operation of 15 the dispenser, that the container be first inverted, see Fig. 1 of drawing, and then that the rubber diaphragm be compressed inwardly and released, causing the fluid to be sucked in and completely fill the dispenser chamber with liquid. 20 After this operation the bottle is uprighted and the dispenser removed therefrom by unscrewing it, whereupon the contents of the dispenser may be emptied by a dropping operation or the complete contents discharged if desired.

In the embodiment of the invention herein shown, 10 indicates a container in the form of a glass bottle, which is shown supported in an inverted position by the hand of an operator, in the act of compressing the flexible disk 11 of the container 12 threadably attached to the neck of the bottle. Referring to Fig. 2 wherein the bottle neck is shown in an upright, rather than inverted position, the several attached parts of the dispenser are clearly illustrated in the cross section, and as will be seen includes an outer threaded shell 14, an inner shell 15 and the beforementioned rubber diaphragm 11, a washer 16 being employed as between the annular top edge of the neck of the bottle, the inner wall of the attaching cap 14 and the underside of the shouldered portion 17 of the inner member 15. The attaching shell 14 includes a depending threaded cylindrical portion 18 adapted to engage corresponding threads 19 formed in the annular surface of the bottle 40 neck. The upper portion of this shell 14 includes an outwardly disposed annular portion forming a shoulder 20 upon which the annular flange 21 of the inner shell is seated. The ribbed annular bottom edge portion 22 of the diaphragm 11 is 45 seated upon the flange 21 and the upwardly disposed edge portion 23 of the shell 14 is rolled over the annular bead of the diaphragm and is pressed down into an annular recess to insure a secure attachment of the diaphragm to the shell and 50 55

to form an integral assembly of the several parts of the dispenser. The inner shell 15 is shaped to form the annular shoulder 17 previously mentioned on its underside and also a depending circular wall portion 24 wherein the washer 16 is seated so as to be retained within the dispenser and to engage the annular top edge of the neck of the bottle when the dispenser is attached as shown in Fig. 2. The central portion of the inner shell is drawn together, funnel-like, to produce a dispensing spout 25 through which the dispenser chamber 26 is filled by the operation of the diaphragm and from which the contents is discharged from the dispenser chamber after it has been filled and removed from the bottle.

The modification shown in Fig. 7 includes a spring 27 that is contained within the liquid chamber 26 formed within the dispenser as between the inner shell 15 and the diaphragm 11. The upper end portion of the coiled spring is centered with respect to the inner central portion of the diaphragm by means of a lug 28 formed upon the inner side of the diaphragm and an annular shoulder 29 formed in the top surface of the inner shell as shown in Fig. 7. This spring is obviously for the purpose of lending resistance to the rubber cap and to prolong its usefulness.

In the operation of the dispenser which first includes the filling of the liquid chamber, the bottle is inverted substantially as illustrated in Fig. 1 and the diaphragm pressed in order to form a vacuum and then released in a way to suck the liquid into the chamber. The container is then uprighted and the same removed from the bottle by unscrewing the dispenser, including the threaded shell, then the dispenser supported over the object upon which the liquid is to be applied, whereupon the operator again presses down upon the diaphragm in a manner to discharge the contents, in the chamber of the dispenser, the amount of pressure exerted upon the diaphragm determining whether the solution is to be discharged in drops or in larger quantities.

Having thus described our invention, what we claim and desire to secure by Letters Patent is:

1. A combined bottle closure and liquid dropper comprising a closure cap adapted for attachment to a container and having an annular outwardly disposed top portion, an inner shell having an outwardly disposed annular flanged portion seated on the outwardly disposed top portion of the cap, a flexible diaphragm having an outwardly disposed annular flange secured between the flanged portions of the cap and the flanges of the inner shell member forming a chamber, the said shell member having a central depending spout communicating with said chamber.

2. A combined bottle closure and liquid dropper comprising a closure cap adapted for attachment to a container and having an annular outwardly disposed portion above its point of attachment to the container, a flexible diaphragm secured on the said annular outwardly disposed portion of the closure cap, an inner shell member including a cylindrical wall to fit the inner cylindrical wall of the closure cap and having an outwardly disposed annular flange portion secured between the flanged portion of the cap and the flexible diaphragm forming a chamber and also having a central depending spout communicating with said chamber.

3. A combined bottle closure and liquid dropper comprising a closure cap adapted for attachment to a container and having an annular out-

wardly disposed portion above its point of attachment to the container, a flexible diaphragm secured on the said annular outwardly disposed portion of the closure cap, an inner shell having a depending spout and an outwardly disposed annular flanged portion secured between the flanged portion of the cap and the flexible diaphragm forming a chamber, an annular shoulder surrounding the inner end of the spout and a spring positioned in the chamber between the diaphragm and the said annular shoulder.

4. A liquid dispenser of the class described, for attachment to a container including a closure cap adapted for attachment to the container and having an enlarged outwardly disposed portion forming a flat shoulder and an annular pocket above its point of attachment to the container, a normally hemispherical form of flexible diaphragm having an outwardly disposed annular rib secured in the annular pocket of the closure cap, an inner shell forming a dropper including a lower depending contracted spout portion, an intermediate annular shoulder, a cylindrical portion to engage the inner wall of the closure cap, and an outwardly disposed annular flange positioned between the cap and the flexible diaphragm, and a gasket positioned between the top end of the container, the closure cap and the annular shoulder of the inner shell.

5. A combined bottle closure and liquid dropper comprising a closure cap adapted for attachment to a container and having an enlarged outwardly disposed portion above its point of attachment to the container and forming an annular shoulder and pocket, a flexible diaphragm having an outwardly disposed annular rib secured in the top of the annular pocket of the closure cap, an inner shell having a depending contracted spout portion, an intermediate annular shoulder, a cylindrical portion to fit the inner wall of the closure cap and an outwardly disposed annular flange positioned between the cap and the flexible diaphragm, and a gasket positioned between the top end of the container, the closure cap and the annular shoulder of the inner shell.

6. A combined bottle closure and liquid dropper comprising a closure cap adapted for attachment to a container and having an annular outwardly disposed top portion, an inner shell having a contracted depending spout portion and an outwardly disposed annular flanged portion seated upon the top portion of the cap, a flexible diaphragm having an outwardly disposed annular rib, the annular flanged portions of the cap being rolled in upon the annular rib of the diaphragm in a manner to secure the cap, the diaphragm and shell together to form an integral unit.

7. A combined bottle closure and liquid dropper comprising a closure cap adapted for detachable engagement to a container, said cap being in the form of a cylindrical shell having container engagement means at one end and an annular outwardly extending flange at its opposite end terminating in an upstanding wall, an inner shell having a depending spout tube, and intermediate annular shoulder, a cylindrical portion to fit the inner wall of the closure cap and an outwardly disposed annular flange adapted to be superimposed on said cap flange, a gasket member seated against said intermediate shoulder and a bulbous shaped flexible diaphragm terminating its open end with an outwardly flaring annulus, the latter being disposed upon said inner shell annular flange and adapted to form an hermetic seal.

therewith by having the upper portion of said upstanding wall formed downwardly thereupon.

8. A combined bottle closure and liquid dropper comprising a closure cap adapted for detachable engagement to a container, said cap being in the form of a cylindrical shell having container engagement means at one end and an annular outwardly extending flange at its opposite end terminating in an upstanding wall, an inner shell 10 comprising a depending spout tube merging at its upper end into a stepped annular seat, an intermediate annular shoulder immediately above said seat, a cylindrical portion to fit the inner wall of the closure cap and an outwardly disposed annular flange adapted to be superimposed on said 15

cap flange, a gasket member seated against said intermediate shoulder, a bulbous shaped flexible diaphragm having an apical inwardly projecting integral knob and terminating its open end with an outwardly flaring ribbed annulus, said annulus being disposed upon said inner shell annular flange and having a hermetic seal therewith by reason of having the upper part of said upstanding wall formed tightly about said ribbed annulus, and a coiled spring member disposed between said 10 stepped annular seat and said diaphragm and having its upper end centralized by said knob. 5
